UNITED STATES PATENT OFFICE.

WILLIAM CALDWELL, OF LEIGH, ENGLAND, ASSIGNOR TO THE RADAX PNEUMATIC TYRE COMPANY, LIMITED, OF WARRINGTON, ENGLAND, JOINT STOCK COMPANY.

LOOM.

SPECIFICATION forming part of Letters Patent No. 712,358, dated October 28, 1902.

Application filed September 10, 1900. Serial No. 29,554. (No model.)

To all whom it may concern:

Be it known that I, WILLIAM CALDWELL, cotton-mill manager, a subject of the Queen of Great Britain, residing at Vicarage Square, 5 Leigh, in the county of Lancaster, England, have invented certain new and useful Improvements in or Relating to Looms for the Manufacture of Textile Fabric for Forming the Outer Covers of Pneumatic Tires or for 10 other Purposes, of which the following is a specification.

This invention has for its object improvements in or relating to looms for manufacturing a curved woven fabric for forming the outer covers of pneumatic tires or other purposes, and relates more especially to looms of the character described in Caldwell's United States Patent, dated June 12, 1900, No. 651,744; and the present invention comprises, *inter 15 alia*, the following improvements: (a) Fixed bobbins carrying the supply of warp-threads and means for producing independent tensions on the warp-threads or on groups or sections of said warp-threads—namely, by forming a loop or bight in each said group or section of warp-threads from each said bobbin and suspending a weight in said loop or bight; (b) a special warp-thread-guiding device between said bights or loops and the loom (ad- 20 vantageously on or near the floor) for keeping the warp-threads or sections of threads clear of one another; (c) coating or providing the step-drum or differential drum around which the warp-threads pass in the loom with an 25 antislipping material, such as cotton velvet; (d) improved means ("temple") for keeping the fell of the cloth flat and the warp-threads flat at this point and keeping the fell of the cloth tightly stretched out laterally at this 30 point; (e) improved horn or curved ridge in conjunction with the take-up ring over which the fabric is drawn and shaped; (f) a system of small convex rolls for guiding the woven fabric from the take-up ring onto the 35 winding reel or "batch"; (g) improved means for operating said winding reel or batch.

In order that the present invention may be fully understood and readily carried into practice, I will proceed to describe the same 40 with reference to the drawings hereunto annexed.

Figure 1 is a side view in elevation of a loom having the present improvements applied thereto. Fig. 2 is a back view of said loom. Fig. 3 is a "local" plan view, on an enlarged scale, of the improved horn and temple. Fig. 4 is a local side view, on an enlarged scale, of the temple and improved horn and showing the take-up ring acting in conjunction therewith. Fig. 5 is a local view 55 in elevation, and Fig. 6 a local view in plan, on an enlarged scale, of the special warp-thread-guiding device for keeping the warp-threads or sections of threads clear of one another; and Fig. 7 is a detail plan view of the convex 60 rolls.

Similar letters of reference indicate corresponding parts throughout.

a is the main frame of the machine, part of said frame extending, if desired, upwardly 70 and rearwardly, as shown in Fig. 1, as and for the purposes hereinafter described.

b b are the fixed bobbins on which the group of warp-threads are wound, each said bobbin *b* being independently journaled or 75 mounted in said frame *a*.

Any suitable means are provided to hold the bobbins *b* in fixed position—*i. e.*, to prevent their rotation or to permit said bobbins to be released by hand and to then revolve 80 when required to draw off a fresh supply of warp-thread *c*. For instance, for each bobbin *b* a spring *d* may be employed, provided with a catch *d'* thereon adapted to lock or engage in the bobbin *b* to thereby normally prevent rotation of said bobbin. 85

The warp-threads *c* pass over a pulley or beam *a'* and have a bight or loop formed therein, in which is suspended a weight *e*, ad- 90 vantageously by means of a pulley *e'*, which rests in said bight or loop on the warp-thread *c*, and the latter after passing under said pulley *e'* thence passes up over a second pulley or beam *a''* and thence descends to or near to the floor, where same (either with or 95 without passing through a horizontally-disposed reed *x*) is led under a crescent-like or stepped flat wooden plate or device *f* (see Fig. 6) or other suitable guiding device, whereby the various warp-threads *c* or groups 100 are prevented from coming in contact with one another as same are drawn into the loom,

and from this point the threads *c* pass into the loom over a roller *g* and around a step-drum or differential drum *h*, (see Figs. 1 and 2,) constructed according to or similarly to 5 or having the characteristic features of the drum shown in the aforesaid United States Patent No. 651,744, and the weaving takes place in the same or similar or equivalent manner to that described in the aforesaid 10 patent. The feature of improvement in the said drum according to the present invention consists in coating or covering or providing the periphery of said drum with any suitable antislipping material, advantageously cotton 15 cut-pile fabric, the back of which fabric is affixed to the step-drum (by any suitable adhesive) with the pile-surface outermost, or any other suitable textile or other material, such as chamois leather, may be employed 20 as desired, the object according to the present invention being to prevent any slip of the individual threads or groups of threads *c* as same pass around said step-drum *h*.
i is the small pin-roller, termed a "temple," 25 for keeping the fell of the cloth and also the warp-threads at this point flat or level and also keeping said cloth extended laterally at this point, such roller *i* being provided around its circumference with pins, burs, or other 30 suitable points, same being advantageously slanting from the middle toward each end—*i. e.*, half of said points slanting to the right and the other half slanting to the left—or said pins or points may be arranged spirally 35 either with or without slanting, by which means the fell of the cloth is not only held down flat, and same and the warp-threads kept level close up to the "beat-up," but also the fell of the cloth is kept stretched out and 40 extended laterally.
j is the horn or curved ridge of special form, as shown on an enlarged scale in Figs. 3 and 4, this device *j* being hollow at its rear or so formed as to be adapted to fit over or partly 45 over the take-up ring *k*, so that the curved woven fabric passes smoothly over said horn *j* onto and around the take-up ring *k*, suitable means being provided to press said fabric against said ring in order to draw off the 50 made fabric, (for instance, a band-brake arrangement *l* may be employed, such as is illustrated in the aforesaid United States Patent No. 651,744,) and from this take-up ring *j* the fabric passes around or partly 55 around a succession of small convex rolls or rings *m*, rotatably mounted in the frame *m*. This frame is pivotally supported upon the frame of the machine by the rod or pivot *m'*, thereby allowing the rolls to rise and fall with 60 the batch, the fabric being finally wound on a batch roller drum or ring *n*, this latter being rotated by the usual or any suitable means for rotating a batch, for which purpose the following improved means may be employed:
65 A crank-rod *o*, operated from any suitable part of the loom, is connected with one arm of a bell-crank lever *p*, secured thereto in a

slot *o'* toward the outer end of said crank-rod *o*, the other arm *p'* of said bell-crank *p* carrying a pawl *p*, engaging in a ratchet-wheel *q*, 70 mounted concentrically with said bell-crank, the latter having a third arm *p* extending therefrom, to which one end of the spring *r* is attached, the other end of said spring *r* being attached to a fixed part of the loom, and 75 thereby the said ratchet-wheel *q* (either directly or through a suitable train of toothed wheels, such as *s s' s*) revolves the batch roll or ring *n*. The tendency of the spring *r* when extended is to rotate (in a constant manner) 80 said ratchet-wheel *q* through the medium of the pawl *p* on the bell-crank arm *p'*, and when such rotation or partial rotation has taken place the periodical reciprocation of the aforesaid crank-rod *o* will force back the bell-crank 85 and again put the spring *r* in tension, and so on.

The operation is as follows: A bight or loop having been formed in each section or group of warps and the relative weights *e* hung in 90 each said loop or bight, respectively, (the amount of each said weight being increased or diminished according to the tension it is desired to put upon the warp-threads *c*.) each bobbin *b* in turn is released by hand (by the 95 operative) so as to allow the warp-threads wound thereon to unwind until the weight *e* in that particular section or group of threads has descended with its bight or loop sufficiently—say nearly to the floor—whereupon 100 further revolution of the bobbin is stopped by means of the catch *d* or other suitable stop or mechanism adapted to hold said bobbin in a fixed position. As the weaving proceeds the warp is drawn steadily from the said bight or 105 loop in each said section or group, respectively, as and when required, and thereby each weight or weighted device is lifted some more rapidly than others, more warp going into the middle or center sections of the fabric than 110 into the outer sections, and consequently the weights on the loops of the center sections are raised more rapidly than those of the outer sections, and the attendant from time to time merely has to release the respective 115 bobbins separately, so that the weights can descend and draw off more warp from each said bobbin in turn as and when same is required, each said bobbin being again fixed and prevented from revolving, and so on 120 throughout all the bobbins as the weaving progresses.

If desired, pulleys or grooved wheels may be used instead of the beams *a*' and *a* at the top of the frame *a*, Fig. 1, over which pulleys or grooved wheels the warp-threads *c* may be passed to form the series of bights or loops, as before.

Having now described my invention, what I claim as new, and desire to secure by Letters 130 Patent of the United States, is—

1. In a drawing-off mechanism for looms, the combination of a curved drawing-off ridge or horn, over which the fabric passes, a roller

beneath said horn having a convex face, a band-brake, and means for holding said brake against the roller or the fabric thereon, a series of smaller rollers having convex faces between which the fabric passes, and means for drawing off said fabric, substantially as described.

2. In a loom, the combination with the feeding mechanism, and a stepped drum over which the threads pass; of a guiding device adapted to operate in conjunction therewith, provided with a stepped surface, and a reed mounted upon said guiding device, adapted to guide the threads upon said stepped surface, substantially as described.

3. In a loom, the combination with the feeding mechanism, and a differential or stepped drum; of a guiding device adapted to operate therewith, said device being provided with stepped surfaces over which the threads pass, a reed mounted above said guiding de-

vice, and provided with a plurality of slats between which the threads pass, before reaching said stepped surface, substantially as described.

4. In a loom for weaving curved fabrics, the combination with the feeding mechanism, and a differential or stepped drum; of a guiding device adapted to operate therewith, said device being provided with stepped surfaces, the curve formed by said stepped surfaces corresponding approximately to the curvature of the fabric to be woven, and a guiding device adapted to guide the threads upon said stepped surfaces, substantially as described.

In witness whereof I have hereunto set my hand in presence of two witnesses.

WILLIAM CALDWELL.
